DESIGN FOR A COMBINATION MERCHANT- DISE AND DISPLAY PACKAGE

Abraham N. Spanel, Rochester, N. Y.

Application June 8, 1934, Serial No. 52,109

Term of patent 14 years

To all whom it may concern:

Be it known that I, Abraham N. Spanel, a citizen of the United States, residing at Rochester, in the county of Monroe and State of New York, have invented a new, original, and ornamental Design for a Combination Merchandise and Display Package, of which the following is a specification, reference being had to the accompanying drawing, forming part thereof.

Fig. 1 is a perspective view of the combination merchandise and display package showing my new design, and Fig. 2 is a bottom view of the same.

The dominant feature of my ornamental design resides in the bulb-like effect of the product, although it is not a simulation of such, but a suggestive motif, only.

I claim:

The ornamental design for a combination merchandise and display package as shown and described.

ABRAHAM N. SPANEL.
